EX
OF D 15,002

Design No. 15,002, dated May 13, 1884.

UNITED STATES PATENT OFFICE.

WALTER P. WARREN, GURDON G. WOLFE, AND ROBERT SCORER, OF TROY,
NEW YORK, ASSIGNEES TO THE FULLER & WARREN COMPANY, OF
SAME PLACE.

DESIGN FOR A PARLOR-STOVE.

SPECIFICATION forming part of Design No. 15,002, dated May 13, 1884.

Application filed August 29, 1883. Term of patent 7 years.

To all whom it may concern:

Be it known that we, WALTER P. WARREN,
GURDON G. WOLFE, and ROBERT SCORER, of
the city of Troy, county of Rensselaer and
5 State of New York, have jointly invented and
produced a new and original ornamental Design
for Parlor Heating-Stoves, of which the
following is a specification.

Our design relates to the ornamental form
10 and surface ornamentation of parlor heating-
stoves, as shown in the two accompanying
plates of photographs, forming a part of this
specification, of which—

Plate 1 shows an end of the stove, and Plate
15 2 a perspective view, with the parts of the
stove designated by letters-reference, and the
detail of ornamentation indicated by numbers,
as follows:

The letter A indicates the stove-top, which
20 is square and tapers inwardly and upward,
and is composed of the apex bar 1, made with
ovalo sides and ends; the inwardly and upward
beveled and mitered band molding indicated
25 at 2; the mitered ogee molding indicated at
3; the mitered ovalo molding indicated at 4,
and shown as ornamented exteriorly with
wave lines and heart-shaped figures 5; the flat
surface-border indicated at 6; the parts design-
30 at 7, and shown as being placed at the
corners, and having pedestal-bases, mortar-
tops, and globe-formed centers.

The letter B indicates an ornamental panel
arranged immediately beneath the overhang
of the top of the stove ends, and consisting of
35 the relief vine, leaves, and tendrils indicated
at 8; the centrally-arranged vine-encircled
leaf ornament designated at 9; the downward
and inwardly beveled band molding indicated
40 at 10 and at the top of the panel, and the
downward and outwardly beveled band mold-
ing indicated at 11, and arranged at the bot-
tom of said panel B.

The letter C designates a design for orna-
menting the ends of the stove above the end
45 doors, consisting of a row of inverted scallops,
as shown or indicated at 12, and the convolu-
tive scrolls designated at 13, with the tops of
the latter within the scallops.

The letter D indicates the door of the stove,
all having the same ornamentation, the double 50
doors closing the front being curved to con-
form to the outcurve of the stove-front, and
the end doors flat. The ornamentation of
the doors consists of a central vertical stile,
short vertical stiles, and horizontal sash-bars, 55
so as to inclose the upper panes 14, one of
which is on each side of the central vertical
stile; the panes 15 15, to which are horizon-
tally arranged each side of the central stile,
and immediately below the top pane, the two 60
square central panes 16, one of which is on
each side of the central vertical stile; and the
arched panes indicated at 17, of which there
are three on each side of the central vertical
stile. The top panes are ornamented with 65
radial disk figures, three in each pane, with
the central one larger than the others, as indi-
cated at 18, with the larger central panes or-
namented with fan-form trefoils in their upper
corners, and intermediately-placed pendent 70
trefoil figures. All the panes are arranged
and ornamented above the arched bottom
panes, may be used as a separate figure of the
design for the same purpose independently
of the arched panes, and the manner of orna-
menting the bottom of the stove-door by means
75 of arched panes, as shown in the annexed pho-
tographs, may, as a separate feature of the de-
sign for such a use, be employed separately,
and without the ornamentation and arrange-
80 ment of the upper panes.

The letter P designates the pilasters, ar-
ranged on the front and ends of the stove at the
corner, their ornamentation consisting of the
grouped quarterfoil figures on the pilaster-
85 caps, as indicated at 19; the filleted base to
the cap, designated at 20; the vertical fluting
shown at 21; the pencils within the fluting
near the bottom of the last, indicated at 22;
the quarterfoil figure and molding inclosing 90
it designated at 23; the scale ornamentation
shown at 24, and the molded plinth indicated
at 25.

The letters H H H indicate panels at the
ends of the stove, below the doors. Their or-
namentation consists of the diagonally-milled 95

and intaglio line bordered surfaces shown at 26.

The letters L² L² L² designate recess-panels at the ends of the stove, above the ash-pit, and 5 ornamented by the relief figure indicated at 27, representing a daisy-form flower and stem on each side of an intermediate leaf and stalk.

The letters J indicate the ash-pit wall of the stove, having the ends exteriorly ornamented 10 by Corinthian volute scroll-work, designated at 28, consisting of the radiate fan-form ornaments indicated at 29, shown as intruded between the top curves, the beaded top 30, and the alternating rosettes and fan-form ornaments 15 designated at 32, and shown as intruded in the bottom in contact with the ends of the reversing-scrolls.

The letter K designates the stove-base curtain, it being shown as ornamented with 20 Corinthian volute scroll figure, having fan-form ornaments between the scrolls at the top, as indicated at 34, with the bottom fillet, 35, the top fillet, 36, with pendent radiate ornaments, indicated at 37, and alternating bead-form ornaments 25 on the bottom fillet, as shown at 38.

The letter L designates a molding having a centrally-formed ornamental arch, indicated at 39, arranged beneath the top at the front, and between straight lateral extensions of the 30 molding, designated at 40 40, which lateral extensions from the arch are at the corners of the stove mitered to the end molding, 11.

The letter M designates the stove-front above the base, having rectilinear corners where 35 united to the ends, and ornamented by the centrally-located outcurves indicated at 41.

The letter N designates an ornamental cap on the top of the outcurve, at the front, said cap having its base curved coincidently with 40 that of the outcurve of the stove, as indicated at 42, and therefrom to curve inwardly and upward to where the cap joins the stove front.

The letter O designates the stove-front immediately beneath the overhang of the top, 45 and which is shown as ornamented with vine-leaf and vine-tendril figures 43, and having vertical ends at the corners and rounded inner ends, 44.

The letter R designates a molding on the front of the stove, coincidently curved with the latter, and arranged between the upper and lower double doors, said molding being composed of the filleted band surfaces indicated at 45, and the upper and lower filleted 55 beveled band-surfaces shown at 46 46.

The letter S designates the lower double doors, which curve with the stove from opposite the fire-pot, their ornamentation consisting of the panes within the door-frame, a central vertical stile, an upper and lower, and short stile at each side of the central stile, and two horizontal sash-bars; and there are within the doors two upper narrow panes 47 47, at 60 each side of the central stile, the middle panes 65 48, of which there is one on each side of cen-

tral stile, and the lower panes 49 49, of which there are two each side of the central stile, as shown.

The letters T designate corner-pilasters on 70 the ash-pit or stove-base, which are ornamented with an antique vase figure in relief, as shown at 50, with relief figures representing flowers at the top of the vase, indicated at 51, and at the bottom of the vase, as shown 75 at 52.

The letter U designates the front of the ash-door, which is ornamented with arched vertical recessed panels, with radiate rosette figures within the tops of the arches, as shown at 80 53, intaglio representation of grasses on the stile between the panels, as indicated at 54, with the door-front bordered with a recessed fillet, 55.

The cap N is ornamented centrally with a 85 relief figure representing a Maltese cross, which is surrounded by rings at 56, and its remaining surface is ornamented with representations of vine, vine leaves and tendrils. As applied to the top of the ornamental out- 90 curve of the stove-front, the form of the cap is purely ornamental. The extended space below may be used for displaying a name, substantially as shown.

Having thus described our design, what we 95 claim as new, and desire to secure by Letters Patent, is—

1. In a design for a stove, the top A, consisting of the apex bar 1, the upward and inwardly beveled and mitered band molding 2, the mitered ogee molding 3, the ovalo molding 4, mitered at the corners and having thereon waved lines and heart figures 5, the flat surface 6 on the four sides of the top, and the globe-formed parts 7, having mortar-form tops on 105 pedestal-bases, substantially as shown and described.

2. In a design for a stove, the ornamental panel B, consisting of the vine, vine leaf and tendril, indicated at 8, and the vine-encircled 110 center leaf ornament 9, substantially as shown and described.

3. In a design for a stove, the ornamentation of the end of the stove above the door, as shown at C, consisting of the inverted scallops 115 12 and the convolute scroll figures 13, substantially as shown and described.

4. In a design for a stove, the ornamentation of the doors D, consisting of the two upper panes 14, the ornamental figures 18 placed 120 therein, the panes 15, the middle square panes 16, and the arched bottom panes 17, as shown and described.

5. In a design for a stove, the ornamentation of the pilasters P, consisting of the quarterfoil figures of the caps 19, the filleted base 125 to the caps 20, and vertical flutings 22, the quarterfoil figure and molding 23, the scale ornamentation 24, and the molded plinths 25, as shown and described.

6. In a design for a stove, the ornamental panels H on the end of the stove, consisting of

- the diagonally-milled surfaces 26 and their intaglio border, and the panels L², consisting of the daisy-form figures and stem and the intermediate wreath and stalk, 27, as shown and described.
7. In a design for a stove, the ornamentation of the ash-pit section at the ends, designated at J, consisting of the Corinthian volute scroll figures 28, the fan-form ornaments 29, intruded between the tops of the scrolls, the beaded tops 30, and the rosettes and intermediate fan-formed ornament 32 at the lower end of the bottom scrolls, as shown and described.
8. In a design for a stove, the ornamentation of the base-curtain K, consisting of Corinthian volute scroll figures having fan-formed ornaments 34 between the scrolls at the top, the bottom fillet, 35, the top fillet, 36, the pendent radiate ornaments 37, and alternating bead figures 38 on the bottom fillet, as shown and described.
9. In a design for a stove, the molding, L, consisting of the central arch, 39, and the lateral extension thereof 40, and the vertical surface O, ornamented with the vine-leaf and vine-tendril figures 43 and curved ends 44, as shown and described.
10. In a design for a stove, the ornamental stove-front M above the ash-pit, consisting of the centrally-arranged and laterally-extended outcurve or swell 41, and the flat and rectilinear extensions thereof, and the cap N, having its base curved coincidently with the swell of the front of the stove, and from the base 35 curved with rotund contour upward and inwardly, and ornamented with the centrally-placed rings surrounding the Maltese cross 56 and the vine 57, substantially as shown and described.
- 40 11. In a design for a stove, the surface ornamentation of the cap N, consisting of the cen-
- trally-placed ring surrounding the Maltese cross 56 and the vine 57, as shown and described.
12. In a design for a stove, the ornamentation of the lower doors, S, consisting of the panes 47 47 on each side of the central stile, the two middle panes 48, and the lower panes 49, as shown and described.
13. In a design for a stove, the ornamentation of the pilasters T, consisting of the figure of an antique vase, 50, with figures 51 in relief at the top, representing flowers, and flowers 52, represented at the bottom of the vase, substantially as shown and described.
14. In a design for a stove, the ornamentation of the ash-door front U, consisting of the recessed and arched panels with rosette-formed figures 53 at their tops, 'grasses 54 on the stiles between said panels, and the recessed border fillet 55, as shown and described.
15. The design for a stove, consisting of a rectilinear base and rectilinear ends, pyramidal-formed top, a rectilinear-formed front where the latter and the ends unite, a centrally-located and laterally-extended outcurve made in the front between the rectilinear sides thereof, above the base and below the top, and a cap on the top of the outcurve, which cap curves inwardly and upward from the outcurve in rotund contour to the rectilinear face of the stove, above the outcurve, as shown and described.

Signed at Troy, New York, this 2d day of August, 1883.
